UNITED STATES PATENT OFFICE.

GEORGE T. GREER, OF ROANOKE, VIRGINIA.

WRAPPING MACHINE.

Application filed March 31, 1921. Serial No. 457,402.

To all whom it may concern:

Be it known that GEORGE T. GREER, a citizen of the United States, residing at Roanoke, in the county of Roanoke and State of Virginia, has invented certain new and useful Improvements in Wrapping Machines, of which the following is a specification.

My invention relates to new and useful improvements in machines for wrapping fruit and especially to machines for wrapping oranges.

One of the numerous objects of the present invention is to construct a wrapping machine provided with a hopper into which will be placed the oranges and from which they will feed two at a time, that is one from each side of the hopper to a spoon located beneath a plunger. In front of each plunger is supported a roll of paper and beyond this is placed a twister so that as the oranges push the paper forwardly and are secured in a clamp the twister while the orange is thus held will twist the wrapper tightly around the oranges. The operation is to be continuous so that each succeeding orange forces the one previously wrapped from the clamp to a box or other desired receptacle.

Still another object of the invention is to so form the machine that the paper in the form of rolls may have printing thereon in certain spaced relation which paper will be cut at the proper place to form the individual wrapper, so that the printing will properly appear on each wrapper.

Still another object of the present invention is to so form and arrange the different parts of the machine that the various steps that is—the feeding of the orange to the spoon below the plunger—from thence to the twister—the cutting of the wrapper—and the twisting of the wrapper, will all follow in their proper time, so that each orange will have a properly cut and properly twisted wrapper thereon.

Still another object of the present invention is to form a stop or cut out mechanism for the machine, so that when desired or necessary to stop the machine, it may be done very quickly, so that in case of a breakdown none of the paper will be wasted nor will the oranges pass through the machine without being properly wrapped.

Still another object of the invention is to so provide a machine wherein the oranges

to be wrapped will be continuously fed to the machine but will not be forced or jammed or even dropped any great distance, which would of course tend to bruise or otherwise injure the fruit.

Still another object of the invention is to so construct the machine that the different steps, from the insertion of the oranges to the hopper to their emission in a wrapped condition, will be quickly performed; no time being lost in any of the successive operations and all of the steps so timed that the oranges will be perfectly wrapped and normally delivered at the rate of about 60 70 per minute.

Still another object of my invention is to provide a wrapping machine wherein the oranges will be centered when they pass from the hopper and rest in the spoon under the plunger. Furthermore, after being forced against the paper and through the twister, a clamp will securely hold an orange while the twister is being operated and from which clamp the orange may be removed by hand or may be left in the clamp to be forced into a container by the succeeding orange.

Still another object of the present invention is to provide an orange wrapping machine wherein the same may be regulated for different sized run of oranges or for larger or smaller fruit than oranges, if desired.

Still another object of the present invention is to so form the fruit wrapping machine that there are two complete sets for wrapping the oranges so that the capacity will be double that of a single machine. This is desired not only for the speed attained but that the oranges if removed by hand, will enable the operator to use both of her hands rather than just one.

With these and other objects in view my invention consists in certain new and novel constructions and combinations of parts as will be hereinafter more fully described and pointed out in the claims.

In the drawings—

Figure 1 is a top plan view of my improved machine showing the plungers in their retracted position, two oranges being shown in dotted lines in position in front of the plungers ready to be forced through the twisters;

Fig. 2 is a side elevation of the machine, also showing a plunger in its rearward po-

sition and an orange being shown on the receiving spoon;

Fig. 3 is a front end view;

Fig. 4 is an enlarged vertical sectional view taken transversely through the hopper;

Fig. 5 is an enlarged detail fragmentary view of a plunger and a twister, partly in section and a part broken away for sake of clearness;

Fig. 6 is a vertical sectional view of the twister looking in the direction of the arrow, Fig. 5;

Fig. 7 is a fragmentary detail view of the driving and stopping mechanism for the machine;

Fig. 8 is a sectional view taken on line 8—8 of Fig. 7;

Fig. 9 is a fragmentary sectional view of the paper feeding and cutting mechanism and its associated parts;

Fig. 10 is a rear view of the same looking in the direction of the arrow, Fig. 9, the casing being removed;

Fig. 11 is a fragmentary top plan of the knife and its associated frictionally held slide; and

Fig. 12 is a fragmentary detail view of the clutch arrangement for the plungers, a portion of the same being broken away for the sake of clearness.

Referring now to the drawings, there is shown a suitable stand or base 1, on the lower portion of which is mounted the small electric motor 2, which in turn drives the suitably mounted wheel 3, which in turn through the belt 4 drives the main shaft 5 on the inner end of which is idly mounted the main drive wheel 6, the said shaft being suitably supported in bearings 7 which are in turn mounted on a cross bar of the frame 1 and a further cross bar 8. About centrally of the frame 1 are the further cross bars 9 which are secured at their opposite ends to the upper side bars of the frame 1, and extending transversely of these cross bars are the two short I-beams 10 which form the track and guides for the two plungers 11. As these plungers are identical, a description of the one will be a description of the other.

Plunger and spoon.

The plunger is preferably provided on its sides with the grooved side plates 12 to receive the opposite edges of the bearing plate 13 which is secured to the top of the eye beam 10 which plate forms a smooth bearing and guide for the plunger. To the under portion 14 of the plunger 11 is secured a spoon 15, which spoon is slotted at 15', for the reception of the pin 16 and the spoon is also further held and vertically adjustable with relation to the under surface of the plunger by the pin 17 on which there is the small tension spring 18. This

spoon extends rearwardly of the plunger and then downwardly as at 20 and contacts with two stops 20' and 20'', and at its forward end is cup-shaped as at 21 to receive and hold the orange. By having the spoons vertically adjustable the different size run of oranges may be properly centered with regard to the twisters.

The plunger, it will be noticed, has a reduced forwardly extending portion 22 as clearly shown in Fig. 1, the forward end of which as will be later described, contacts with the orange when the same rests in the spoon 21 to force it through the twister and into a clamp. On the outer side of each of the plungers is placed a gear rack 23 that extends from the rear of the plunger to the inner end of the reduced portion 22. Mounted on the frame 1 and located to the side of this plunger is positioned the bearings 24 in which revolves a shaft 25, and on this shaft is pinned a sleeve 26 in which sleeve is placed the small spring-pressed clutch pin 27. A gear 28 is idly mounted on the shaft 25 and formed integrally with this gear is a small clutch wheel 29 having a beveled opening 30 formed therein for the reception of the spring-pressed clutch pin 27. The gear 28 is always in mesh with the aforementioned rack 23 but idles when the plunger is traveling in one direction as will be shortly described.

Referring for the moment to the main drive wheel 6, it will be seen that mounted thereon is the connecting rod 31 which in turn is suitably connected to the shaft 32 which extends from the inner side of one plunger to the inner side of the opposite plunger, the ends of this shaft fitting within the bosses 32'. The revolution therefore of the shaft 5 and the drive wheel 6 will cause the plungers 11 through the connecting rod 31 to move forwardly and rearwardly, the speed of course depending upon the rate of speed applied to the drive wheel 6.

The small gear wheels 28 in mesh with the gear racks 23 will idle on the forward movement of the plunger due to the clutch pin 27 slipping over the bevel surface of the opening in the clutch face 29, but on the return movement of the plungers the gear wheels 28 will function, as the pin engaging the clutch wheel will hold the same and revolve the shafts 25. On these shafts 25 are mounted the beveled gears 33 which in turn drive the shafts 34 through the gears 35 mounted on their ends and in mesh with the bevel gears 33.

Located near the forward end of the machine are the two uprights 36 in which rest the shaft 37 on which is positioned the paper rolls 38.

Secured to the main frame and directly in front of the plungers are the two twisters

39 which will be shortly described in detail. These twisters are each provided with a sprocket wheel 40 over which passes the chain 41 which in turn is driven by the sprocket wheel 42 which is driven by the heretofore mentioned shaft 34.

As far as the specification has proceeded, it will be seen that on a revolution of the drive wheel 6, the plungers 11 on their forward movement will not operate the twisters as the small spring-pressed pin 27 will not engage its cooperating clutch face 29, but on the return of the plungers the gear will be in fixed engagement with its shaft 25 and through the shaft 34 will cause the sprocket 40 through the intervention of the chain 41 to revolve, the operation of the twister being performed by the revolution of the sprocket.

On the outer end of each of the shafts 25 there is a further sprocket wheel 43 over which passes a chain 44 which engages a sprocket wheel 45 mounted on the opposite end of the rollers 45', which rollers are mounted in a box 54 which box is secured on the frame, as will be shortly described. Small clutches may be provided on the ends of the rollers 45' which will be operated by the small hand rollers 46, the arrangement being similar to the clutch used on the typewriter platen so that any small adjustment of the rolls may be made. It is to be understood that any form of clutch arrangement desired might be used on these rolls or platens.

35 It is to be remembered that these rollers 45' to unwind the paper are also only operated on the return movement of the plungers, similar to the action or movement of the twisters.

40 Further, mounted in the box 54 and contacting with the rollers 45' are the further platens or rollers 100 so that the paper will be gripped and fed downwardly on the revolution of the rollers 45'.

45 Beneath the rollers 45' and in front of the twisters there is shown the partitions or double walls 47 through which the paper from the rolls 38 will pass, and in the wall are formed the two round openings 48 which are directly in front of the plungers 11 and through which opening the plungers, and fruit pass.

Wrapper cutting.

55 Referring now to the manner of cutting the paper into successive wrappers, it is of course desired that they each be of the same size so that the trade-mark, name or other printed matter that may have been previously and successively printed on the rolls will properly appear on each wrapper. To do this therefore it is necessary that the cutting be properly done and work in synchronism with the twisting of the wrapper.

65 Referring first to Fig. 2 it will be seen

that mounted on the main frame between and below the plungers is a small bracket 49 in which is pivoted the upright yoke arm 50 which in turn is provided with a small link 51 which is secured to a yoke 52 which straddles the hopper 53 which hopper is located above the plungers and supported by the uprights 53', a spring 50' holding the arm 50 in its normal position. It might be here mentioned that the hopper may be of any conventional design, provided its lower portion is bifurcated to form two passageways so that the oranges may be fed to the spoons 15 secured to the plungers 11; the openings of these passageways being, of course, in the path of movement of the said spoons. If, however, the machine should be built with but one plunger, then one passageway from the hopper would be sufficient.

85 Located near the periphery of the drive wheel 6 is a small roller 150 which is spaced slightly over 90° from the pivotal connection of the connecting rod 31, and this roller is arranged to contact with and to force the yoke arm 50 inwardly as the plungers 11 make their forward movement.

At the upper end of the walls or partition 47 is placed the aforementioned box 54 which extends completely across the machine and is secured to the uprights 36, the connection between the uprights and the box being of a slot and pin nature so that the box may be slightly elevated or lowered if desired. An opening 55 is formed in one face of the box 100 for the inner end of the aforementioned yoke arms 52 to which are secured the horizontally positioned knife 56, as clearly shown in Fig. 11.

105 Grooves 58 are formed in the opposite sides of the box for the reception and guidance of a wooden block 60, while further slots 61 are also provided for the opposite end of the knife 56. A small metal plate 62 is shown mounted on the block 60 and below the knife 56 so that the block 60 will not be subjected to the continuous friction of the knife.

115 Referring to Figs. 9 and 10 especially, it is to be noticed that the knife is in fixed relation to the yoke 52 but the block 60 is provided with two spring clamp arms 63 that engage the upper surface of the knife 56 but allow the same to move slightly forwardly and rearwardly with relation to the block 60.

120 Two stops 64 are provided in the grooves 58 so that as the yoke is pulled rearwardly the block 60 will move rearwardly, being frictionally clamped to the knife, but on contact with the stop 64 will stop and allow the knife to still continue in its rearward movement.

125 A wooden stop in the form of a block 65 is provided as clearly shown in Fig. 9, so that the paper from the rolls 38 passing through

- the box and through the wall 47 will be adjacent with the face of this block 65. A small slot or groove 66 is shown in this block so that the knife 56 may pass therethrough, 5 and the block 60 frictionally carried by the knife will, on the forward movement of the yoke arm press the paper against the block 65 and tightly hold the same while the knife forces or shears its way through the paper.
- 10 In other words, by providing the frictionally held block 60 to the knife 56, just as the paper is cut or sheared it will be tightly held between the forward edge of the block 60 and the face of the aforementioned block 65.
- 15 The block 60 will then move rearwardly when the knife is moved rearwardly to allow the new wrapper to be fed, but as before mentioned this block does not travel the same distance as the knife.
- 20 As the paper is fed downwardly its weight together with the action of the rolls will provide an effective and proper feeding of the paper to the knife and as soon as it is sheared it will be forced by the orange to the 25 twister, the cutting action being so timed that the paper will not be allowed to drop beyond the openings 48, but on the other hand is cut just in time to be free to pass with the orange into the twister by the 30 plunger, 11.

Twisters.

Referring now to the twisters and especially to Figs 5 and 6, it will be seen that each 35 one comprises a standard 69 secured to the frame which standard is provided with the circular housing 70 in which there is provided a sleeve or ring 71, on the outer end of which is formed the aforementioned sprocket 40. This sleeve is provided with a small outer flange 71' which bears against a portion of the outer surface of the housing 70, and about its inner periphery and nearly midway of its width are the pins 72 which 45 contact with an inner wall 73 of the housing, which wall is formed by cutting or coring out a portion on the inner surface of the housing 70 as shown at 74. In this portion 50 of the housing 70 are arranged the three slots 75, see Fig. 6, these slots being spaced at points about the circumference of the housing and in three separate vertical planes, the lower one being at the outer edge of the portion 74 while the other two are in planes 55 slightly nearer the wall 73. Formed in the sleeve 71 there are also formed three openings 76 which openings are also in three different vertical planes taken through the sleeve, each of these latter slots or openings 60 registering with one of the previous slots mentioned, 75.

Extending through each of the three openings 76 is the small trip arm 77 which in turn is secured to a main twisting arm 78 of 65 the twister. These arms 78 are clearly

shown in Fig. 6 and are bent substantially semi-circular in shape and as they are distributed or located at three different points about the sleeve they will assume the position shown in Fig. 6 when closed.

The small trip arms 77 are each connected by a spring 79 to the rotatable sleeve 71 so that when the sleeve is in its normal or starting position, the springs will pull the small arms inwardly and thereby pull the 75 arms 78 to their open position. This is possible because the small arms 77 will each be opposite its slot 75 of the housing, and the small arms will extend therethrough. As soon as the twister is operated, however, through its sprocket, the small arms 77 will be forced out of the slot which will swing the main arms to their closed position in which position they will remain until the sleeve has made one complete revolution 80 when each one of the small arms will again be in front of its corresponding slot when the springs again will return the arms 78 to their open position. The inner surface of the cylinder is slotted transversely at three 85 points for the reception of the transverse portion 78' of the arms 78 and the slots on the inner surface of the sleeve are slightly beveled transversely so that the arms 78 with their little trip arms 77 may swing to a 90 full open and closed position. Two small transverse slits 82 are formed in the sleeve to receive the ends 81 of a small circular band 80 which is then placed within the sleeve which holds the arms 78 tightly in 95 place in their respective slots and also presents a smooth and unbroken surface to the orange as it is passed through the twister.

It is to be remembered that the twister makes one complete revolution on the return of the plunger 11 so that when the orange on its forward movement with the plunger 11 passes through the twister, the arms 78 are in their open position but immediately on the return of the piston the arms 78 swing to their closed position and remain in this position until the completion of the revolution when they again swing open.

Referring now to Figs. 1, 2 and 3, there is shown directly in front of the two twisters the small clamps 83 which may consist of two upright arms 84 which are held together at their lower ends by the rods 85, and midway through the arms 84 is placed the rod 86 which is provided with the small springs 87 which abut against the washers 88 and the upright arms 84 so that as the orange is forced through the twister it will be pushed into this flexible clamp, and there held while the twister is operated as above described.

Any form of suitable clamp may be used, and if desired a plurality of them, one in front of the other, might be provided, so that the oranges will be successively forced from one clamp to the other from which 130

they might be removed by hand, or a plurality of clamps might be formed on one base so that as the clamps are filled up the base with the oranges might be removed.

5 In Fig. 2, however, I have shown but one clamp and directly in front of the clamp there is shown a small bag 89 open at the bottom, the lower end of the bag extending into a box 90 which may be supported on 10 the track 91 and held in position by the trip 92 which when released will allow the box 90 to slide to an endless conveyor 93, from which the box will be removed. By providing a bag in front of each twister the oranges will not be jammed or bruised when 15 dropping into the box.

Referring now to Figs. 2, 7 and 8, there is shown a small starting and stopping arrangement which consists of a small clutch 20 wheel 94 mounted on the main shaft 5. Secured between this wheel 94 and to the inner face of the drive wheel 6 is a small circular plate 95, and provided on its inner face with an opening 96. Extending transversely of 25 the wheel 94 is the spring pressed pin 97 which is placed in a suitable opening 94', and extending through an opening 98 in the periphery of the wheel 94 is the small lug 99 which is formed on the pin 97. Located 30 beneath the wheel 94 is the curved plate 110 which has an inner beveled inclined surface 111. This plate 110 is free to slide forwardly and rearwardly, it being held in the 35 guide 112 secured to the cross bar 8 of the main frame. Connecting with this plate 110 is the control rod 113 which extends to the forward end of the machine and to its outer end is fastened the handle 114.

When it is desired to stop the machine the 40 handle 114 is simply forced inwardly which causes the pin 97 when it contacts with the beveled surface 111 to retract so that it no longer engages with the walls of its opening 96 in the plate 95. The main shaft 5 will of 45 course continue to rotate but the drive wheel 6 which is idly mounted, as will be remembered, on the shaft 5 will of course idle until the rod 113 is again pulled outwardly which will allow the clutch pin 97 to again spring into the opening 96, at 50 which time the machine will again start its various operations.

At the outer end of the main drive shaft 5 is shown a handle 115 which may be used 55 in case it is desired to revolve the shaft 5 a slight distance, or if desired to run the machine by hand.

Reviewing briefly the operation of the 60 machine, it is as follows: On the starting of the motor 2, assuming the different parts of the machine to be as shown in Fig. 2, on a part revolution of the drive wheel 6, the small roller 150 will force the arm 50 inwardly causing the yoke 52 with the knife 65 thereon to sever the paper. The plungers 11

will move forwardly and the orange resting on the spoon will be advanced through the twister. The rear end 20 of the spoon 15 then contacting with the small stop 20' located beyond the gear rack so that the orange 70 will be pushed off the spoon by the continued outward movement of the plunger. The orange will then be tightly held in the clamp 83, it having forced the wrapper around the orange as it passes through 75 the walls and the twister, the rearward portion of the wrapper however still extending within the twister. On the return movement of the plunger 11 however the small clutch will cause the rack 23 and the gear 28 to function which causes a complete revolution of the rotatable sleeve 71 of the twister, the arms of the twister closing at the beginning of the revolution, and the action of the arms tightly twisting the 80 wrapper about the orange.

Furthermore, as described, the paper feeding mechanism also operates on the return movement of the plunger, a new wrapper being lowered to the opening 48 in front 85 of the twister.

Also on the return of the plunger the rearward portion of the spoon 20 contacts with the small stop 20' so that the spoon will again be forced in front or advance of 90 the plunger and in its receiving position for the next orange.

This cycle is continuous, the paper being 95 cut during a part of the forward movement of the plunger and the twisting and the feeding of the paper on the rearward movement of the plunger.

From the foregoing it will be seen that the machine is one that may be easily controlled, operates rapidly, successively cuts the 100 wrappers of desired size and firmly twists the wrapper about the orange.

Many slight changes might be made without in any way departing from the spirit or scope of the invention.

Having thus described the invention, what is claimed as new is:

1. In a wrapping machine the combination of a base, a plunger mounted for horizontal movement on said base, a hopper opening in front of said plunger, paper feeding and cutting mechanism, a twister mounted in front of said plunger and thrown into operation by a stroke of said plunger, means for receiving and holding the articles to be wrapped while said twister is operating and means for driving said plunger.

2. In a wrapping machine the combination of a base, plungers mounted for horizontal movement on said base, a hopper provided with diverging passage-ways opening in front of said plungers, paper feeding and cutting mechanism, twisters mounted in front of said plungers and thrown into op-

eration on certain strokes of said plungers, means for receiving and holding the articles to be wrapped while said twisters are operating and means for driving said plungers.

3. In a wrapping machine the combination of a base, a plunger mounted for horizontal movement on said base, a hopper opening in front of said plunger, means for feeding the paper in front of the plunger, means for cutting the paper, means for temporarily supporting the article to be wrapped in front of the plunger, means for twisting a wrapper on the article, means for holding the article while the twisting means is operating and means for driving the plunger to advance the article to be wrapped and to set into motion the paper feeding means, the paper cutting means, and the paper twisting means.

4. In a wrapping machine the combination of a base, a plunger mounted for horizontal movement on said base, means connected to the plunger for supporting the article to be wrapped, paper feeding and cutting mechanism, means for holding the article to be wrapped after leaving the supporting means connected with the plunger, means for twisting on a wrapper and means for driving the plunger to advance the article to be wrapped and to throw into operation the paper feeding and cutting mechanisms, and twisting means.

5. In a wrapping machine the combination of a base, a plunger mounted for horizontal movement on the base, a hopper feeding to the plunger, means for supporting the article to be wrapped, said means normally extending in front of the plunger, paper feeding and cutting mechanism, twisting means located in front of the plunger, said plunger adapted to force the article to be wrapped through the twisting means, means for supporting the article to be wrapped after the article has passed through the twister, means for driving the plunger and the twisting means operated on the return movement of the plunger.

6. In a wrapping machine the combination of a base, a plunger horizontally mounted on said base for advancing the article to be wrapped, a hopper feeding in front of the plunger, means for temporarily supporting the article to be wrapped, paper feeding mechanism, paper cutting mechanism and paper twisting mechanism, means beyond the twisting mechanism for holding the article to be wrapped after being advanced by the plunger while the twister mechanism operates, the paper feeding mechanism and the twisting mechanism operating on the movement of the plunger in one direction and the cutting mechanism operating on the movement of the plunger in the other direction and means for operating the plunger.

7. In a wrapping machine the combination of a base, a plunger mounted on said base for advancing the article to be wrapped, a hopper feeding in front of the plunger, means for holding the article to be wrapped in front of the plunger, a drive wheel connected to said plunger, paper cutting mechanism operated by said drive wheel while the plunger is making its forward movement, paper feeding mechanism, operated through the medium of said plunger on its rearward movement, paper twisting mechanism, means for holding the article to be wrapped after being advanced through the twisting mechanism by said plunger and said twister mechanism also operated on the return movement of said plunger.

8. In a wrapping machine the combination of a base, plungers mounted on said base for advancing the articles to be wrapped, a hopper feeding to said plungers, means carried by the plungers for supporting the articles to be wrapped and means for limiting the forward and rearward movement of said supporting means so that the plungers will push the articles to be wrapped off the supporting means on the complete forward movement of the plungers and will return the supporting means in front of the plungers on the limit of the rearward movement of the plungers, paper feeding mechanism operated on the return movement of the plungers, paper cutting mechanism operating on the forward movement of the plungers, twisting means, clamps for holding the articles to be wrapped after being advanced by the plungers, through the twisters, the twister means operated on the return of the plungers, and means for driving the plungers and operating the cutting mechanism.

9. In a wrapping machine, the combination of a base, a drive wheel, horizontal plungers connected to said drive wheel, a hopper feeding from its sides to the plungers, spoons carried by said plungers, stops located below said spoons to limit their forward and rearward movement, a paper feeding mechanism located in front of the plungers and above the same so that the paper will feed downwardly, twister means located beyond the paper feeding mechanism and directly in front of the plungers, said twister means having an opening larger than the articles to be wrapped, paper cutting mechanism operated by said drive wheel and on the forward movement of said plungers, driving means connected with the plungers and the paper feeding mechanism, and driving means connected with the plungers and the twisting means to operate the paper feeding mechanism and the twisting means on the rearward movement of the plungers, and means for hold-

ing the articles to be wrapped when the twisting means is operating.

10. In a wrapping machine the combination of a base, a drive shaft, a drive wheel 5 idly mounted on said shaft and means for holding said drive wheel in locked relation to said shaft, plungers operated by said drive wheel, a hopper feeding to said plungers and means connected to the plungers and 10 movable therewith for receiving the articles to be wrapped, twisting means located in front of the plungers and a drive means connected with said plungers and said twisting means so that said twisting means will operate 15 on a rearward movement of said plungers, adjustable paper feeding mechanism and drive means for said paper feeding mechanism connected with said plungers and adapted to operate on a return movement 20 of said plungers, and clamping means for receiving the articles to be wrapped while the twisting means is operated.

11. In a wrapping machine the combination of a base, a drive shaft, a drive wheel 25 idly mounted on said shaft and means for locking said drive wheel thereto, plungers driven by said drive wheel, and a hopper feeding to said plungers, means carried by said plungers for receiving the articles to 30 be wrapped, stops for said means so that said plungers will force the articles from said receiving means and return said receiving means to their normal position, paper feeding mechanism to supply the paper for 35 the wrappers, adjustable cutting mechanism for said wrappers, twisting means located in front of the plungers through which the front end of the plungers, receiving means and the articles to be wrapped pass, means 40 on said drive wheel to operate the cutting mechanism during the forward movement of said plungers, a rack on said plungers, gears operated by said rack and clutch means between said twisting means and 45 said gears so that said twisting means operates on the return movement of said plungers and means for holding the articles to be wrapped while said twisting means operates.

50. 12. In a wrapping machine, the combination of a base, a drive shaft and a drive wheel located on said drive shaft, a paper cutting means comprising a knife, a frictionally held block carried by said knife and said knife operated by means located 55 on the drive wheel, a paper feeding mechanism, plungers driven by said drive wheel and means operated by said plungers for operating said paper feeding mechanism on a stroke of the plungers, twisting means located in front of the plungers, comprising arms normally held in an open position, clamping means located in front of the twisting means, means connected with the 60 plungers to rotate said arms of the twister 65

and swing them to their closed position to twist on the wrapper when the plungers make their return stroke.

13. In a wrapping machine the combination of a base, a drive shaft, a drive wheel 70 idly mounted on said shaft and means for locking said wheel to said shaft, a paper cutting means comprising an arm operated from said drive wheel, once to a revolution, a yoke arm connected to said arm and a 75 knife carried by said yoke, a block loosely mounted on said knife and a second block mounted to the base so that on a forward movement of the said knife the two blocks will abut, paper feeding mechanism operated by the return stroke of said plungers, twisting means located in front of the plungers, said twisting means provided with arms capable of a rotating and an opening and closing movement, means connected with said 80 twisting means and said plungers to close said arms and cause them to make one revolution on the return movement of the plunger, a hopper feeding to the plungers and means carried by the plungers to hold the 85 articles to be wrapped till passed through the plungers, and means for holding said articles while the arms of the twister are making their revolution in their closed position.

14. A wrapping machine comprising in part the combination of a base, plungers mounted on said base, a hopper feeding the articles to be wrapped to the plungers, paper feeding mechanism operated by a stroke of 90 said plungers, paper cutting mechanism operated during a portion of the movement of said plungers, twisters, each comprising a housing, a sleeve in said housing and a 100 sprocket on the outer end of said sleeve, arms pivotally mounted in said sleeve and extending therethrough, said housing provided with slots through which the inner ends of 105 said arms extend when the sleeve is in its normal position, means for rotating the sleeve of the twister thereby causing the arms of the twister to swing to their closed position until the ends of the arm again are opposite the slots formed in the housing.

15. A wrapping machine comprising in part the combination of a base, a plunger mounted on said base and means for driving said plunger, paper feeding mechanism, paper cutting mechanism, the former operating on the forward stroke of the plunger 115 and the other operating on the return stroke of the plunger, a twister comprising a housing, a rotatable sleeve in said housing, arms passing through openings in said sleeve and normally into openings in said housing, 120 springs connecting with the inner ends of the arms and the rotatable sleeve, said arms having a portion bent substantially semi-circular, said arms being loosely mounted 125 in said sleeve so that they may assume a 130

closed position with relation to each other, means connected with the plunger for rotating said sleeve to thereby force the inner ends of the arms without the slots in the 5 housing to thereby swing them to their closed position and remain closed for one complete revolution of said sleeve, said sleeve making one complete revolution on a rearward stroke of said plunger.

10 16. A wrapping machine for fruit comprising the combination of a base, two tracks mounted on said base, two plungers mounted on said tracks, a gear rack mounted on the outer side of each plunger, a bearing mounted to the side of each plunger, a shaft on each of said bearings and a bevel gear near the outer end of each of said shafts, a sprocket on the outer end of each of said 15 shafts, a gear on the inner end of each of said shafts and meshing with said racks, a clutch cooperating with each of said shafts and with the gears meshing with the racks so that

said shafts will operate only on the return movement of said plungers, paper feeding mechanism located above said plungers and operated by the sprockets mounted on said shafts, twisters located in front of the plungers and operated by the bevel gears on said shafts, a paper cutting mechanism normally held in a retracted position, a main drive wheel for driving the plungers, means on said drive wheel for operating the cutting mechanism on a portion of the forward stroke of said plungers, a hopper for feeding the fruit to the plungers, means carried by the plungers for receiving the fruit from the hopper, and stops for limiting the movement of said means, clamps for holding the fruit after passing through the twister and while the twister operates, and means for 20 starting and stopping the main drive wheel.

In testimony whereof I affix my signature.

GEORGE T. GREER.
